Primary Examiner — Khawaja Anwar*Assistant Examiner* — Taylor O Mortorff(74) Attorney, Agent, or Firm — Aronberg Goldgehn Davis & Garmisa(57) CLAIM

The ornamental design for a tool as shown and described.

DESCRIPTION

FIG. 1 is plan view of a tool in a first state incorporating my ornamental design; and,

FIG. 2 is a perspective view of a tool in a second state incorporating my ornamental design.

The features shown in broken lines in the foregoing drawings form no part of the claimed design.

1 Claim, 2 Drawing Sheets(56)
